FLUID TYPE CAR COUPLING

Maurice F. Powell, Millville, N. J.

Application April 21, 1941, Serial No. 389,685

6 Claims. (Cl. 60—54)

This invention relates to a fluid type car coupling which is mainly designed for transmitting the power from a motor vehicle motor to the wheels of the vehicle though it is to be understood that the invention can be used wherever power is to be transmitted from a power plant to a member to be driven.

The general object of the invention is to provide means whereby the driven member can be driven in a forward direction in variable speeds and can also be placed in neutral.

Another object of the invention is to so construct and arrange the parts that a single unit can be used or a number of units so that the apparatus may be made up to suit any special requirement.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a fragmentary elevational view with parts in section showing a power plant constructed in accordance with the invention.

Figure 2 is a sectional view through the rear part of Figure 1 showing the interior construction and arrangement of the parts.

Figure 3 is a section on the line 3—3 of Figure 2.

Figure 4 is a view looking toward the face of the blade arrangement of the fluid coupling, with the parts associated therewith, portions of the apparatus being shown in section and parts broken away.

Figure 5 is a fragmentary sectional view showing some of the movable blades with the gearing and portions of the spiral stationary blade.

Figure 6 is a detail view showing one of the movable blades and its gearing.

Figure 7 is a sectional view showing a portion of the stationary spiral blade arrangement.

Figure 8 is a longitudinal sectional view through one of the oil pump actuated pistons in a cylinder.

Figure 9 is a sectional view through the cylinder and piston for operating the clutch.

Figure 10 is a longitudinal sectional view through the other cylinder and piston of the oil pump operating assembly.

Figure 11 is a longitudinal sectional view show-

ing a multiple arrangement of the fluid drive means.

Figure 12 is a detail view showing how a ring gear meshes with a pair of segmental gears for operating a pair of movable blades.

Figure 13 is a fragmentary detail view showing how a ring gear is operated by a gear on a longitudinally extending shaft as shown in Figure 11.

10 In these drawings the letter M indicates a motor and the letter H indicates a housing connected with the rear end of the motor and into which extends the shaft S of the motor. A casing C is located in the housing H and the motor shaft extends into the casing and anti-friction means 1 are located between a part of the casing and the rear end of the shaft and a pinion 2 is connected to said rear end of the shaft beyond the anti-friction means 1. Anti-friction means 3 are also arranged between the front of the casing C and a sleeve 4 which is slidably arranged on the shaft S, and is manually shiftable forwardly and rearwardly by suitable means which includes a lever 5 connected with a collar 6 fitting in a groove in the front end of the sleeve. The casing C has a fluid chamber 7 in its front part which is surrounded by a substantially circular chamber 8 which is also of substantially circular shape in cross section but the inner circumference of which is flat and opens out into the chamber 7. Preferably the casing C is formed of two sections, the dividing line passing through the chamber 8 and the chamber 7 and the two sections are fastened together by the bolts 9. An annular core 10 passes through the chamber 8 and this core is also divided into two parts by the dividing line between the two sections and a spiral blade 11 encircles the core and has its inner circumference connected therewith and its outer circumference to the walls of the chamber 8. A notch or opening 12 is formed in each portion of the spiral blade between the core 10 and the point where the chamber 8 opens into the chamber 7 and each notch has its side walls converging to the core with the wall at the core flat as shown more clearly in Figure 2. Thus the spiral blade 11 is divided into a plurality of separate parts by these notches.

40 A wheel W is rotatably arranged in the chamber 7 and includes the hub 13 surrounding and fastened to the shaft S and spokes 14 radiate from the hub.

45 This wheel carries a plurality of vanes 15 each of which has outwardly converging side edges 50 and a straight outer edge so that a vane will fit

in a notch 12, as shown in Figure 2 when the vane is in a certain position or in a position extending at right angles across the chamber 8. Each vane has a pivot 16 on its inner edge which is located off-center of the vane and these pivots connect these vanes with the wheel. A segmental gear 17 is attached to each pivotal point and extends along the inner edge of the vane. These gears 17 mesh with a ring 18, the gears and ring having beveled teeth. Said ring is movably supported on the wheel and has teeth on its inner circumference as shown at 18' with which gears 19 mesh. These gears 19 are also carried by the wheel for rotary movement and each gear is suitably connected to one end of a lever 20 which has a weight 21 at its other end and a spring 22 connects the lever with a part of the wheel. A control rod 23 is provided for each lever and the outer end of each rod has a slot 24 therein for receiving the pin 25 of the lever, said pin being arranged intermediate the ends of the lever. A bellcrank 26 has one arm connected to the inner end of each control rod 23 and the bellcrank is pivoted to a projection 27 on the wheel and the other end of the bellcrank fits in a groove 28 in the inner end of the sleeve 4 so that as the sleeve 4 is moved inwardly and outwardly the bellcranks rock to move the control rods 23 inwardly and outwardly.

Thus the levers 20 can be actuated by manual means to cause partial rotary movement of the gears 19 and, of course, such gears 19 are also controlled by centrifugal force through the weights 21 and the springs 22, the slots 24 in the rods 23 permitting centrifugal action.

The rear part of the casing C contains a gear chamber 30 closed at its rear by a plate 31 fastened to the rear part of the casing and a sleeve 32 is rotatably arranged on the driven shaft 33, the sleeve having a socket therein to receive the front end of the driven shaft and said sleeve at its front end has a gear 34 connected therewith which meshes with the gears 35 on the stub shafts 36 journaled in the rear plate 31 of the casing C and an intermediate plate of the casing. Larger gears 37 are carried by the shafts 36 and mesh with the pinion or gear 2. Thus if the casing C is held stationary the shaft S will drive the sleeve 32 through the gearings 34, 35 and 37 through means of the gear 2. The sleeve 32 is journaled in the plate 31 and also in a plate 40 extending across the rear part of the housing H and a housing 41 is connected with the rear end of the sleeve and is provided with the blades 42 with which cooperate the blades 43 carried by a member 44 which is rotatably arranged on the shaft 33 through means of a hub 45 to which a gear 46 is connected, said gear meshing with the gears 47 on the stub shafts 48 carried by a member 49 keyed to the shaft 33. A small casing 50 is connected with the rear part of the casing 41 and encloses the gears 46 and 47 and the member 49 and said casing has a ring gear 51 therein which meshes with the gears 47. The casing 41 contains fluid, such as oil, and thus the blades 42 and 43 provide a fluid drive between the sleeve 32 and the casing 41 and the driven shaft 33 and with the gearing in the casing 50. A clutch plate 52 is keyed to the sleeve 32 and lining 53 is located between the plate 52 and the plate 31. Spring means 54 move the clutch plate 52 in one direction and levers 55 move the plate in an opposite direction. These levers 55 are moved by a collar 56 slidably arranged on the tubular part 57 extending forwardly from the plate 40 and a shift

lever 58 actuates the collar as shown more particularly in Figure 3 through means of a fork 59. The member 58 is operated by a link 60 connected to the rod 61 of a piston 62 in a cylinder 63 which is suitably supported adjacent the motor. A conduit 64 connects the cylinder 63 with a cylinder 65 above a ported piston 66 in the cylinder 65, the port of the piston being shown at 67. A pump 68 pumps oil from the oil sump 69 through a pipe 70 into the cylinder 65 but when the piston 66 is in the position shown in Figure 10 this oil will simply overflow and return to the sump. However, if the piston 66 is in a position where its port 67 will connect the pipe 70 with the conduit 64 then the oil will flow into the cylinder 63 so as to cause the parts 61 and 60 to apply the clutch 52 against the casing C.

A rod 71 extends upwardly from the piston 66 and has a slot 72 in its upper end which slidably receives a pin 73 in a lever 74 which is connected at one end by a link 75 to a bellcrank 76 which is connected with the throttle operating means by a link 77. The other end of the rod 74 is connected as at 78 with a rod 79 which passes through a cylinder 80 and is connected to a piston 81 in the cylinder. A pipe 82 connects the bottom of the cylinder 80 with the lubricant pump 83 of the motor. A spring 84 tends to hold the piston 81 in its lowered position and this piston controls a vertically arranged port 85 in the cylinder 80, the width of which can be adjusted by means of a sleeve 86 surrounding the cylinder and held in adjusted position by a screw 87, said sleeve having a slot 88 therein for registering more or less with the slot or port 85, in the cylinder 80. A release valve 89 is provided for the pump 68 and a manually controlled valve 90 is arranged in the conduit 64 leading from the cylinder 65 to the cylinder 63. A by-pass 91 by-passes the valve 90 and a check valve 92 is arranged in the by-pass for permitting quick release of pressure in the cylinder 63 to the cylinder 65 when the piston 66 lowers. A rod 93 controls the valve 90, this rod 93 being manually controlled in any suitable manner.

When the control lever connected to the member 5 is in forward position and the engine is idling, springs 22 will hold the weighted levers 20 in position to cause the vanes or blades 15 to feather into straight line position so that no motion is imparted to the fluid and the driven assembly remains idle. As the engine revolutions increase the weighted levers swing out and through means of the pinions 19, gear wheel 18 and the segmental gears 17 the vanes 15 are moved from a neutral or straight position to an angular position, thereby setting up a flow of fluid through the driven blades 11 for imparting motion to the casing and, of course, this speed of driven assembly or casing C increases as the vanes 15 impart more motion to the fluid under increased motion of the engine or shaft S. With the arrangement shown when the engine shaft begins to impart motion to the casing C the planetary gearing, driven from the shaft S and its gear 2 will cause the casing C to move in reverse due to the resistance offered by the sleeve 32 and its attachment to the driven shaft 33 which has the load thereon. However, as the speed of the assembly increases and the load starts to move the casing C will for a while cease to move and then starts to move in the same direction as the shaft S and this continues until the casing and the parts connecting it with the load or shaft 33 is rotating at full speed.

Of course, the sleeve 32 when rotating from the casing will impart movement to the casing 41 and when the casing 41 reaches a certain speed the fluid therein will cause motion of the member 44 of the tubular part 45 and the planetary gearing including the parts 46 and 47 and ring gear 51 will act upon the member 44 to cause it to gradually move in a forward speed until the planetary gearing and the shaft 33 will be rotating at the same speed as the sleeve 32.

The angle of driving blades or vanes 15 is dependent on the speed of both the driving shaft S and the driven assembly including the casing C, due to the blades being mounted off-center. Thus with a slow speed in the driven unit and a higher speed in the driving unit increased resistance to the driving blades 15 will result and stop the outward movement of the weighted levers until the speed of the driven unit increases. The centrifugal strain will always lead and attempt to bring the speed of the driven unit up to the speed of the driving unit. The weighted levers and the parts associated therewith are designed to vary the leverage as the weights swing outwardly in a manner resulting in setting up a balance at high speed to maintain a full speed position of the driving blades or vanes 15.

With the control means for the clutch member 52 and the parts associated therewith properly conditioned when the engine is started both oil pumps 68 and 83 will be operated. The operation of the pump 83 will cause the piston 81 to rise until the port 85 is uncovered to allow the oil to return to the engine sump. The level to which this piston rises depends on the engine speed and the amount of opening of the port 83 by sleeve 86. The oil from the pump 68 passes to cylinder 65 above piston 66 and overflows the cylinder to the sump. Thus with the engine running and valve 90 opened, as the engine is speeded up to start the car through the fluid drive the piston 81 will rise which raises lever 74 at point 78 and piston 66 will also move upwardly. However, since lever 74 is connected to the throttle the amount the piston 66 is raised is dependent on the amount of throttle opening in relation to engine speed since the level of the piston 81 is dependent on engine speed.

Now assume that with a sufficient throttle opening to propel the car twelve miles per hour on a level road in high gear, piston 81 would be floating at the lower end of port 85 and that the connecting link has been adjusted to bring piston 66 up to a point where the port 67 would connect ports or conduits 64 and 70 so that oil will flow to the cylinder 63 to cause the piston 62 to move to position to engage the clutch assembly associated with the clutch plate 52. From this position the car would continue to operate with the clutch engaged. However, if the throttle is opened more than an amount sufficient to lower lever 74 to a point where the connection 73 would use up all the clearance of the slot 72 piston 66 would then move down and vent the cylinder 65 and thus the clutch would disengage.

Since the level at which piston 81 rides depends on engine speed, the higher the engine speed the more the throttle will have to be opened to cause the clutch to disengage and above a predetermined speed the clutch could not be caused to disengage. If during acceleration the car was operating with the clutch disengaged and the throttle was closed enough to use up all the clearance in slot 72 the piston 66 would move up to connect the ports or conduits 64 and 70

through the port 67 and this would cause the clutch to engage.

From the foregoing it will be seen that the car will operate with clutch engaged or disengaged at the will of the operator by a mere change of throttle opening within predetermined limits.

When this control is used with dual unit fluid drive as shown in Figure 2, as the clutch is disengaged, the driving blades 15 will take the load and as the operator wished or unity speed was restored the clutch would again engage without jerk or jar to driving parts.

Figures 11, 12 and 13 show an arrangement in which a plurality of fluid drive means are used and in these views a large casing C' is used which has a plurality of annular chambers 8' surrounding the same. Each of these annular chambers contains the spiral blade arrangement 11' and the drive shaft S' has a plurality of wheels W' connected therewith, each of which carries the movable vanes or blades 15' actuated by centrifugal levers carried by the shaft 103 journaled in the spokes of wheels W', said shaft carrying the gears 101 for meshing with the ring gears 181 which, in turn, mesh with the segmental gears 17' connected with the vanes 15'. Planetary gearings 102 connect the rear end of the drive shaft S' with the driven shaft 103. The operation of this arrangement is similar to that before described excepting that the units are multiplied.

As will be seen this apparatus has a positive neutral and positive and variable speeds. By using gears the work to be done by the movable blades is reduced which lessens slippage. Also by using gears of low ratio with the feathering blades high torque at low driven shaft speed may be obtained. Also the construction and arrangement of the parts will allow a unit to be built in any number of stages to meet various conditions. By using the planetary gears when starting from rest the driven blades rotate in reverse. This coupling has the ability to transmit more power at no revolution of the driven shaft than is possible when the driven blades are attached to the driven shaft and torque transmission is merely the result of slapping the fluid against the driven blades. By the use of a clutch which operates semi-automatically all slippage is prevented and by using a second fluid unit with gears the torque may be increased at the start the same as if reduction gears were employed, and by using the multiple stage construction the work to be done by each stage is reduced, thereby decreasing heat losses and increasing the efficiency of the apparatus.

A spring 60' connects the arm of the rod 58 with an exterior part of the housing, as shown in Figure 1, this spring acting to hold the clutch in inoperative position until the piston 62 and cylinder 63 are actuated to move the clutch part to operating position.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. In a fluid coupling, a rotary casing having an annular fluid chamber having its inner pe-

riphery open, a spiral annular blade extending around the chamber having notches in those parts at the opening, a rotary member surrounded by the chamber, vanes carried by the rotary member and passing through the space formed by the notches as the member rotates and means for adjusting the vanes as to their angular relation to the blade.

2. In a fluid coupling, a rotary casing having an annular fluid chamber having its inner periphery open, a spiral annular blade extending around the chamber having notches in those parts at the opening, a rotary member surrounded by the chamber, vanes passing through the spaces formed by the notches, eccentric pivots for connecting the vanes to the rotary member and means for adjusting the vanes on their pivots.

3. In a fluid drive, a power shaft, a fluid containing casing rotatable about said shaft and including an annular circumferential chamber open at its inner circumferential portion, a spiral blade extending around said chamber and having notches in the convolutions thereof facing the open portion of the chamber, said blade forming a runner, a spider fast on said shaft within said casing and including radial arms, driving vanes at the outer ends of said arms adapted to be revolved in said notches by said spider under rotation of said shaft and mounted on said arms for rotation thereon about the axes of said arms to variably pitch the same, and means to rotate said vanes comprising gearing carried by said spider and rotatable therewith.

4. In a fluid drive, a power shaft, a fluid containing casing rotatable about said shaft and including an annular circumferential chamber open at its inner circumferential portion, a spiral blade extending around said chamber and having notches in the convolutions thereof facing the open portion of the chamber, said blade forming a runner, a spider fast on said shaft within said casing and including radial arms, driving vanes at the outer ends of said arms adapted to be revolved in said notches by said spider under rotation of said shaft and mounted on said arms for rotation thereon about the axes of said arms to variably pitch the same, and means to rotate said vanes comprising gearing carried by said spider and rotatable therewith, said gearing comprising gear sectors operatively connected to said vanes, an annular gear for driving said sectors

relative to said spider, and devices tending under rotation of said spider to rotate said gear.

5. In a fluid drive, a power shaft, a fluid containing casing rotatable about said shaft and including an annular circumferential chamber open at its inner circumferential portion, a spiral blade extending around said chamber and having notches in the convolutions thereof facing the open portion of the chamber, said blade forming a runner, a spider fast on said shaft within said casing and including radial arms, driving vanes at the outer ends of said arms adapted to be revolved in said notches by said spider under rotation of said shaft and mounted on said arms for rotation thereon about the axes of said arms to variably pitch the same, and means to rotate said vanes, comprising gearing carried by said spider and rotatable therewith, said gearing comprising gear sectors operatively connected to said vanes, an annular gear for driving said sectors relative to said spider, and devices tending under rotation of said spider to rotate said gear, said devices comprising a gear pinion meshed with said ring gear and centrifugal throw means to operate said pinion.

6. In a fluid drive, a power shaft, a fluid containing casing rotatable about said shaft and including an annular circumferential chamber open at its inner circumferential portion, a spiral blade extending around said chamber and having notches in the convolutions thereof facing the open portion of the chamber, said blade forming a runner, a spider fast on said shaft within said casing and including radial arms, driving vanes at the outer ends of said arms adapted to be revolved in said notches by said spider under rotation of said shaft and mounted on said arms for rotation thereon about the axes of said arms to variably pitch the same, and means to rotate said vanes comprising gearing carried by said spider and rotatable therewith, said gearing comprising gear sectors operatively connected to said vanes, an annular gear for driving said sectors relative to said spider, and devices tending under rotation of said spider to rotate said gear, said devices comprising a gear pinion meshed with said ring gear and centrifugal throw means to operate said pinion, and manual means to operate said centrifugal throw means independently.

MAURICE F. POWELL.
